UNITED STATES PATENT OFFICE.

OTIS A. MYGATT, OF NEW YORK, N. Y.

DESIGN FOR A REFLECTOR FOR ARTIFICIAL LIGHTS.

SPECIFICATION forming part of Design No. 35,682, dated February 4, 1902.

Application filed June 3, 1901. Serial No. 63,047. Term of patent 7 years.

To all whom it may concern:

Be it known that I, OTIS A. MYGATT, residing at New York, in the county of New York and State of New York, have invented and produced a certain new and useful Design for a Reflector for Artificial Lights, of which the following is a specification, reference being had therein to the accompanying drawings.

The design consists in the form and ornamentation of a transparent reflector for artificial lights.

Figure 1 is a plan of the reflector embodying the design. Fig. 2 is a partial elevation and partial section of the reflector.

The reflector is of transparent glass. The body A is nearly the frustum of a cone, but is surmounted by a ring B. The frusto-conical body A is substantially covered on its outer surface by projecting four-sided pyra-

mids C, joined at their bases. The lower edge 20 of the cone is crimped or fluted, so as to present a sinuous line D, as seen from the side, and the edge is beaded, as indicated.

The inner face of the reflector is smooth, but the design shows through the transparent 25 material, as in part attempted to be indicated in dotted lines.

What I claim, and desire to secure by Letters Patent, is—

The design for a reflector for artificial 30 lights, as shown and described.

In testimony whereof I affix my signature in presence of two witnesses.

OTIS A. MYGATT.
